UNITED STATES PATENT OFFICE

WILLIAM M. TRAYNOR, OF CORNWALL ON THE HUDSON, NEW YORK

COMBINATION GARMENT

Application filed March 17, 1930. Serial No. 436,267.

This invention relates to combination garments, which might be termed unitary garments, and particularly to such garments as are adapted for men's wear.

5 The invention contemplates particularly the combination, into a unitary garment, of an overshirt and a pair of drawers; but some features of the invention are equally adaptable to undergarment union suits.

10 It is known that others have contemplated the broad ideas of combining into a unitary garment an overshirt and a pair of drawers; but none of these has provided the desirable and unique features of the present invention.

15 For example, in some of these previously proposed garments the posterior portion of the drawers portion was in effect a continuation of the shirt portion, which resulted in the drawers riding out of the trousers or pulling

20 up to the resultant discomfort of the wearer and unseemly exposure of the garment. In others the means provided for opening the seat of the drawers was cumbersome or uncomfortable.

25 An object of the present invention is to provide a garment which will serve, when worn, as an overshirt in close simulation of the usual shirt, but with certain additional advantages, and which will also serve as a 30 pair of drawers having a novel and unique form of opening means.

The invention consists in the novel features, arrangements and combination of parts embodied by way of example, in the article hereinafter described, as illustrating preferred forms of the invention, and the invention will be more particularly pointed out in the appended claims.

40 Further and more specific objects, features and advantages will more clearly appear from the detailed description given below taken in connection with the accompanying drawings which form a part of this specification.

45 Referring to the drawings:

Fig. 1 is a front perspective view of a preferred embodiment of the invention.

Fig. 2 is a rear perspective view of the garment illustrated in Fig. 1.

50 Fig. 3 is an enlarged view of the same in

rear elevation with certain parts broken away,

Fig. 4 is a similar view in front elevation, Figs. 5 and 6 are views similar to Figs. 1 and 2, but showing a modification, and

55 Figs. 7 and 8 are views similar to Figs. 3 and 4, but showing the modification of Figs. 5 and 6.

Referring to the drawings, and more particularly to Figs. 1-4, inclusive: the garment comprises broadly a shirt portion 1, and a drawers portion 2; the shirt in the present embodiment being an overshirt provided with an attached collar 3. It will be understood that the invention comprehends an overshirt with or without attached collar; and furthermore that certain features of the invention to be more fully described following may be advantageously utilized or embodied in a unitary garment wherein the shirt 1 may either 60 be an overshirt or an undershirt.

65 The frontal section of the garment is shown as being formed in a manner quite common in making the usual union suit, wherein the frontal shirt and drawers sections are formed 70 in continuation one of the other; the oppositely disposed marginal edges being indicated at 5 and 6.

75 The rear or posterior portion of the shirt portion 1 is designated in Fig. 3 as 7, and is attached along its oppositely disposed marginal edges to the frontal section of the shirt as indicated at 5 and 6, from underneath the respective sleeves downwardly to a position designated as the waist position 8-8.

80 The posterior portion 7 extends 85 downwardly in the form of a shirt tail 9 which preferably has its marginal edges 10 and 11 attached to the frontal portion 4 of the garment substantially down to the end of the tail, so as to provide what might be termed a 90 closed tail; and the tail 9 is sufficiently long to extend to substantially that position of the posterior drawers portion which will be termed the seat portion and is designated as

95 12. The posterior drawers portion is made of substantially inelastic material and is secured along its oppositely disposed marginal edges 14 and 15 to the frontal section 4, such as along the lines 5 and 6, from the position 8-8 down-

100

wardly; providing what might be termed a closed seat for the drawers. The upper marginal edge 16 of the posterior portion is cut on the bias, i. e. tapers downwardly from the waist line position 8 toward the median position designated 13-13a; the lowermost point being in a vertical position intermediate the waist line position 8 and the seat position 12, and in the present embodiment (Fig. 3) being on the median line 13-13a.

10 In the present embodiment of the invention the width of the tail 9 between the points 10-11 and the width of the posterior portion of the drawers between the points 14-15 are each substantially equal to the width of the frontal section 4 adjacent these respective points.

20 By forming the posterior portion of the drawers in this unique manner I have found that it is possible to utilize what I term a closed seat portion or panel, i. e. one that is permanently fastened at its oppositely disposed marginal edges and without having to provide elastic means in order to lower the seat portion when desired. This is what is meant by substantially non-elastic material; which term is not to be understood as excluding the use of a material such as knitted fabric, netting, or the like.

30 Due to the peculiar form and position of the upper marginal edge of the posterior portion of the drawers, the seat may be easily and almost automatically lowered when desired, and when the wearer assumes the desired and usual position necessitating such lowering.

Modification

40 The garment illustrated in Figs. 5-8 is in all major respects similar to that illustrated in Figs. 1-4 inclusive, except as will more fully appear following. For purposes of comparison and facility in understanding the invention the corresponding numerals of Figs. 1-4 inclusive will be utilized with the prime (') suffix added to designate corresponding and similar parts.

50 Referring particularly to Fig. 7: it will be seen that the upper marginal edge 16' of the drawers is cut on the bias from the waist line position 8' downwardly toward the median line 13'-13a'; but in the present embodiment (Fig. 7) the bias is in one direction and continues to the opposite marginal edge 15', the lowermost position of the bias edge still preferably being located above the seat position of said drawers.

55 Similar results in lowering the seat of the drawers are obtained in this modification as in the embodiment previously described; the 60 two presently preferred embodiments being illustrated to show at least two embodiments which have been actually made, and to demonstrate that the invention contemplates embodiments other than that illustrated in Figs. 65 1-4, inclusive.

In both forms the tail 9 and 9' is provided of such length as to cover the biased edge 16 or 16' and to extend downwardly a sufficient distance—in the vicinity of the seat portion—to not only cover the biased edge but also to 70 securely hold the overshirt in the trousers. It will be noted also that in the modification (Fig. 7) the shirt tail 9' is cut on a bias corresponding to the bias of the drawers edge 16'. 75

Having thus described my invention with particularity with reference to its preferred form, and having illustrated one modification thereof, it will be obvious to those skilled in the art, after understanding my invention, that other changes and modifications may be made therein without departing from the spirit and scope of my invention, and I aim in the appended claims to cover such changes and modifications as are within the scope of 80 the invention.

85 What I claim is:

1. A unitary garment comprising a shirt portion and drawers portion, said drawers portion having a relatively inelastic posterior portion permanently fastened along its marginal edges and terminating at its upper edge on the bias at least one side of which is adjacent the waist line position of said drawers, and the median portion of which is intermediate said waist line position and the seat of said drawers, and said shirt portion being provided with a tail adapted to extend downwardly over the lowermost portions of said biased edge. 90

95 2. A unitary garment comprising a shirt portion and drawers portion, said drawers portion having a posterior portion permanently fastened along its marginal edges and terminating at its upper edge on the bias at least one side of which is adjacent the waist line position of said drawers, and the median portion of which is intermediate said waist line position and the seat of said drawers, said shirt portion being provided with a tail adapted to extend downwardly over the lowermost portions of said biased edge, and said tail having its oppositely disposed marginal edges attached adjacent the sides of said drawers. 100

115 In testimony whereof I have signed my name to this specification.

120 WILLIAM M. TRAYNOR.
